CHRISTIAN AALBORG, OF WILKINSBURG, PENNSYLVANIA, ASSIGNOR TO WESTINGHOUSE ELECTRIC AND MANUFACTURING COMPANY, A CORPORATION OF PENNSYLVANIA.

ADJUSTABLE JOINT.

1,107,241.

Specification of Letters Patent. Patented Aug. 11, 1914.

Application filed December 21, 1910. Serial No. 593,517.

To all whom it may concern:

Be it known that I, CHRISTIAN AALBORG, a citizen of the United States, and a resident of Wilkinsburg, in the county of Allegheny and State of Pennsylvania, have invented a new and useful Improvement in Adjustable Joints, of which the following is a specification.

My invention relates to adjustable joints and it has special reference to such devices as are adapted to be used in connection with small fan motors for the purpose of adjusting or "setting" the fan to any desired angle.

16 The object of my invention is to provide a device of the above-indicated class that shall be simple and durable in construction and may be readily adjusted and firmly clamped in position.

20 In the prior art, it has been common to provide means whereby fan motors could be made to assume any desired position, but usually such adjustments have been accomplished by means of two or more separate 25 joints or clamping devices. Obviously, the employment of a plurality of adjustable joints complicates the construction, adds difficulty to the "setting" operation and requires additional space which raises the 30 center of gravity of the fan motor to an objectionable height.

According to my invention, I provide a small, compact and readily adjustable joint which embodies a U-shaped supporting 35 member having vertical side portions between which a disk member is pivotally mounted upon a pin of relatively large diameter. A vertically disposed cylindrical recess is provided in the disk member and a similar opening through the pin registers therewith in such manner as to receive a 40 projecting stem which may be rigidly associated with the motor frame.

It is manifest, therefore, that adequate 45 provision is made for rotational movement and for adjustments of the angle of inclination, so that, by suitably combining both, any desired "setting" may be effected.

50 In order to secure the joint by a single means, the pin upon which the disk member is mounted is provided with a thumb screw which serves to clamp or to release the entire device, as hereinafter set forth. It will, of course, be understood that my 55 invention is not restricted to use with fan motors, but is so set forth only as illustrative

of a particularly useful commercial application to which it may be adapted.

In the accompanying drawings, Figure 1 is a view, in side elevation, of a fan motor which embodies my invention, Fig. 2 is a fragmentary sectional front view of the adjustable joint shown in Fig. 1, and Figs. 3 to 7, inclusive, are detail views of component parts of the joint shown in Figs. 1 and 2.

Referring to the drawings in detail, a fan motor 1 of any common type of construction is mounted upon a suitable base 2 of pressed or drawn sheet metal by means 60 of an adjustable joint 3 which comprises a supporting member 4, a disk member 5, a pin 6, a stem 7 and a wing nut 8.

The supporting member 4 is of U-shape and is rigidly secured to the upper portion 75 of the sheet metal base 2 to form an inexpensive, light and durable unitary structure. The member 4 is provided with an integral downwardly projecting portion 4^a which fits tightly within the upper end of 80 the sheet metal base 2 and also with upwardly projecting side portions 9 and 10, between which the disk member 5 is pivotally mounted upon the pin 6. Axially located in the disk member 5, at substantially 85 right-angles to the axis of the pin 6, is a cylindrical recess 11 for the purpose of receiving the stem 7 which is suitably secured, at its upper end, to the lower portion of the motor frame 12. The pin 6 is 90 of relatively large diameter and is provided with a transverse opening 13 of the same diameter as the recess 11 which is so located as to register therewith in order that the stem 7 may project therethrough. 95 One end of the pin 6 is provided with a small retaining screw 14 which is adapted to project into an annular groove 15 in the stem 7 in order to secure the base 2 to the fan motor 1 without interfering 100 with the rotational adjustment thereof, as will be readily understood. The other end of the pin 6 is of considerably reduced diameter and is provided with a threaded portion 16 upon which the wing nut 8 is 105 screwed in the usual manner.

Assuming the various parts of the adjustable joint to occupy the positions shown, it is evident that the joint is firmly clamped together, inasmuch as one side portion of 110 the disk member 5 is clamped between the upwardly projecting portion 10 of the sup-

porting member 4 and the stem 7 by means of the drawing action effected through the agency of the wing nut 8 and the pin 6.

If it is desired to change the "setting" 5 of the fan, it is only necessary to loosen the wing nut 8, thereby releasing the various parts of the device, after which the fan may be adjusted to any desired position and inclination by virtue of the peculiarities of 10 the adjustable joint hereinbefore described.

While I have shown and described a device of specific construction and arrangement and location of parts, it is evident that various modifications may be effected 15 without departing from the spirit and scope of my invention, and I desire that only such limitations shall be imposed as are indicated in the appended claims.

I claim as my invention:

20 1. The combination with a member having a plurality of substantially parallel arms, a second member pivotally mounted between said arms and having a cylindrical recess therein substantially normal to its pivotal support, and a stem rotatably set in said recess, of means for clamping said parts together and means for preventing longitudinal movement of said stem.

25 2. The combination with a member having upwardly projecting side portions, a second disk-like member having a central opening therein disposed between said portions, and a third member rotatably mounted in the opening of said second member, of a relatively large pin projecting through said side portions and constituting a pivotal support for said disk-like member and having a transverse opening therein to receive said third member, and means for clamping said 40 parts together.

30 3. The combination with a supporting member having parallel arms, a pin projecting therethrough and having a transverse opening of relatively small diameter therein, 45 a second member pivotally mounted on said pin in intimate contact with said arms and having a recess to register with the transverse opening in said pin, and a stem rotatably disposed in said recess and projecting 50 through said transverse opening in said pin, of clamping means associated with one end of said pin for locking the parts firmly together, and means associated with the opposite end thereof for preventing longitudinal 55 movement of said stem.

35 4. The combination with a U-shaped member, a pin extending through the side portions thereof and having a transverse opening therethrough, a second member 60 pivotally mounted on said pin intermediate the side portions of said U-shaped member, said second member being provided with a recess disposed normally to said pin and

registering with the transverse opening in said pin, and a cylindrical stem rotatably disposed in said recess and projecting through said transverse opening, of a single means for clamping all said parts together. 65

5. The combination with a U-shaped member having parallelly disposed side portions, a disk member located between said side portions and having a cylindrical recess therein, a pin extending through said side portions upon which said disk member is pivotally mounted, said pin having a transverse opening of relatively small diameter to register with the recess in said disk member, and a stem rotatably disposed in said recess and projecting through the transverse opening in said pin, of clamping means associated 70 with said pin for locking the various parts in position.

6. The combination with a member having a plurality of substantially parallel arms and a second member pivotally supported 85 between the said arms, of a stem associated with the said pivotally supported member, a body pivotally secured to the said pivotally supported member by means of the said stem, and means for clamping the said pivotally supported member between the said parallel arms.

7. The combination with a member having a plurality of substantially parallel arms and a second member pivotally supported 95 between the said arms, of a stem associated with the said pivotally supported member, a body pivotally secured to the said pivotally supported member by means of the said stem, means for clamping the said pivotally supported member between the said parallel arms, and means for preventing disengagement between the said body and the said 100 pivotally supported member.

8. The combination with a member having 105 a plurality of substantially parallel arms and a second member pivotally supported between the said arms, of a stem associated with the said pivotally supported member, a body pivotally secured to the said pivotally 110 supported member by means of the said stem, means for clamping the said pivotally supported member between the said parallel arms, and means for preventing disengagement between the said body and the said 115 pivotally supported member, comprising an annular groove formed in the said stem and a retaining screw coöperating with the said groove.

In testimony whereof, I have hereunto 120 subscribed my name this 9th day of Dec., 1910.

CHRISTIAN AALBORG.
